SILENCER FOR FIREARMS, COMBUSTION
ENGINES, AND THE LIKE

Henri Coanda, Clichy, France

Application April 19, 1935, Serial No. 17,362
In France October 8, 1934

7 Claims. (Cl. 181—60)

This invention relates to silencing devices for fire arms, combustion engines and the like and has for its object to provide an improved arrangement for silencing the outflow of a stream 5 of gas issuing from a tube or other outlet into the surrounding atmosphere. My invention is based upon the lamination of said gas stream into thin sheets.

If a gas flowing at high velocity is projected 10 into the atmosphere through a very narrow slit, the sheet which escapes through said slit can be given a predetermined direction by braking it on the desired side, the optimum curve to be described by the outflowing sheet of gas being a 15 function of the physical constants of said gas and of those of the surrounding atmosphere, as well as of the velocity and mass of the gas stream. By suitably choosing these factors, it is therefore possible thus to change the direction of the direct 20 reaction of the gases escaping into the surrounding atmosphere, and to permit their escape without noise.

If the gases are guided for a substantially long period, so that their expansion may absorb part 25 of their heat, which further facilitates their evacuation, there is obtained both an improvement in efficiency and outlet velocity and the absence of noise.

In the case of silencers for firearms or for combustion engines it will therefore be sufficient to provide in the path of the gases an escape towards a chamber, this chamber being provided with slits so arranged and constructed that they impart to the sheets of gas escaping into the atmosphere a predetermined direction due to braking of the gaseous sheet on one side thereof. In this manner the shock wave which occasions the sharp report of fire-arms, guns, etc., is wholly eliminated.

The silencers for firearms or combustion engines according to the present invention therefore include a chamber which may eventually serve for the partial expansion of the gases, into which the exhaust pipe or the barrel of a gun or firearm opens through a series of suitably arranged orifices, said collecting chamber in turn opening into the atmosphere through a series of narrow slits, the outer surface of said chamber being provided with projections of curved section 50 each of which is provided on only one side of a respective slit.

In order that the invention may be more clearly understood a silencer for a firearm and for a combustion engine will now be described with 55 reference to the accompanying drawing wherein

Fig. 1 is a section through a fire arm silencer, Fig. 2 is a detail of Fig. 1, Fig. 3 is a section through a combustion engine silencer and Fig. 4 is a section on the line IV—IV of Fig. 3.

Referring to Fig. 1, the barrel 1 of a fire arm 5 is provided, at a short distance from its muzzle 2, with annularly arranged orifices 3, through which the gases escape into an expansion chamber 4, formed between the barrel 1 and a sleeve 5 arranged on the barrel. The expansion chamber 10 10 4 opens into the atmosphere through substantially narrow slits 6 which are inclined to the axis of the chamber 4. The outer face of the sleeve 5 is provided with a projection 8 located adjacent the outlet of each of said slits 6 on 15 the side thereof nearest the butt end of the gun (see Fig. 2). This projection 8 causes the sheet of gas escaping through slit 6 to move substantially tangentially to the walls of the said projection 8, following the path indicated by the arrow F.

Since these exhaust gases react in the opposite direction to the recoil, they create by their displacement a vacuum at f (Fig. 2) avoiding the creation of a shock reaction which would 25 propagate itself, as in the case of ordinary firearms, by giving rise to the well known crack of present day fire arms. In this manner the effect of the recoil is considerably reduced at the same 30 time as the shock wave is eliminated.

In Fig. 3 and 4 a similar arrangement is applied to the exhaust gases of combustion engines; the gases coming from the engine pass through a pipe 9, into the annular expansion chamber 10 which communicates with the atmosphere through slits 35 11. When the gases escape through slits 11 they are guided by projections 12 which are of a shape comparable to those described with reference to Fig. 2, and produce the silencing effect. The annular chamber 10 may be constituted by rings 13 40 arranged on an axis 14 and held by means of a fixing nut 15 placed at the end of the axis. Between the various rings 13, spacing washers 16 are arranged, their thickness corresponding to the width of slits 11. The rear part of the silencer 45 is preferably given a profile as shown at 16 in order to facilitate the flow of the gases without the production of eddies.

I claim:

1. A silencer for the outflow of gases under 50 pressure from an outlet into the atmosphere, which comprises, in combination, a chamber communicating with said outlet, said chamber being provided with a plurality of narrow passages connecting the inside of said chamber with the out- 55

side thereof, said passages opening into the atmosphere in a direction making an angle different from zero with the outer surface of said chamber, and a projection of curved section on the outer 5 surface of said chamber, adjacent to only one side of each passage, respectively, all of these projections being on the same side of the corresponding respective passages, whereby a portion of the gases escaping from said chamber through said 10 passages are caused to flow along said projections.

2. A silencer for the outflow of gases under pressure from an outlet into the atmosphere, which comprises, in combination, a chamber communicating with said outlet, said chamber being 15 provided with a plurality of narrow passages connecting the inside of said chamber with the outside thereof, said passages opening into the atmosphere in a direction making an angle of at least 90° with the direction of flow of the gases 20 issuing from said outlet and an angle different from zero with the outer surface of said chamber, and a projection of curved section on the outer surface of said chamber adjacent to each passage 25 on the side thereof corresponding to the direction from which the gases enter said chamber, whereby a portion of the gases escaping from said chamber through said passages are caused to flow along said projections in a direction substantially opposed to that in which they flow from said outlet into said chamber.

3. A silencer for an internal combustion engine which comprises, in combination, a chamber communicating with the exhaust of said engine, said chamber being of substantially cylindrical shape, 35 said chamber being provided with a plurality of annular slits connecting its inside with the atmosphere surrounding it, said slits extending radially in a direction transverse to the axis of said chamber, and annular projections of curved axial section each adjacent to the outlet of an annular 40 slit on the outer surface of said chamber, all of said annular projections being on the same side of said slits, respectively, whereby a portion of the

exhaust gases escaping from said chamber through said slits are caused to flow along said projections.

4. A silencer according to claim 3 in which said chamber is formed of a plurality of ring-shaped 5 elements, means for assembling said elements together, and washers interposed between said elements so as to leave the desired slits between them.

5. A silencer for a device ejecting gases in sudden or explosive manner, comprising the combination, of an annular chamber of predetermined length, means for introducing gases under pressure from said device into said chamber within the annular bounding wall of the latter, said 15 bounding wall being pierced by at least one aperture disposed transversely to the axis of said annular chamber and intermediate the ends thereof so as to connect the interior of the chamber with the atmosphere and allow gases from said chamber to escape through said aperture, and a projection of curved section with respect to an axial plane disposed upon the outer surface of said annular chamber adjacent to the aperture in the bounding wall thereof and providing a smoothly 20 curved continuation of solely the forward side of the wall of said aperture with respect to the direction of movement of the gases within the annular chamber, whereby a portion of the gases escaping from said chamber through said aperture 25 are caused to flow along the exterior of said projection and then along the exterior of the annular chamber, said aperture making an angle which is at maximum a right angle with respect to the axis of said chamber.

6. A silencer according to claim 5, wherein the bounding wall is pierced by a plurality of spaced annular apertures.

7. A silencer according to claim 5, wherein the bounding wall is pierced by an annular aperture 40 in the form of a slit.

HENRI COANDA.
